[57] CLAIM

The ornamental design for a watchcase, as shown and described.

DESCRIPTION

FIG. 1 is a front elevational view of a watch case showing my new design in a de-activated condition;

FIG. 2 is a top plan view thereof;

FIG. 3 is a left side elevational view thereof;

FIG. 4 is a right side elevational view thereof;

FIG. 5 is a bottom plan view thereof;

FIG. 6 is a rear elevational view thereof;

FIG. 7 is a top plan view thereof in an activated condition;

FIG. 8 is a top plan view of a second embodiment of my new design of FIGS. 1-7.
